LATCH BOLT UNIT

Original Filed Aug. 11, 1950

UNITED STATES PATENT OFFICE

2,665,154

LATCH BOLT UNIT

Getthard Hagstrom, Greenwich, Conn., assignor
to The Safe Padlock and Hardware Company,
Lancaster, Pa., a corporation of Pennsylvania

Original application August 11, 1950, Serial No.
178,897, now Patent No. 2,644,704, dated July
7, 1953. Divided and this application February
14, 1952, Serial No. 271,492

11 Claims. (Cl. 292—169)

1

This invention relates to certain improvements in latch bolt units; and the nature and objects of the invention will be readily recognized by those skilled in the arts involved in the light of the following explanation and detailed description of the accompanying drawing illustrating what I now believe to be the preferred embodiments or mechanical expressions of the invention from among various other embodiments, modifications, variations, combinations and constructions of which the invention is capable within the broad spirit and scope thereof as defined by the claims hereto appended.

This application is filed as a division of my co-pending application Serial No. 178,897, filed August 11, 1950, for Door Latch Mechanisms, now Patent No. 2,644,704, issued July 7, 1953.

The invention is particularly concerned with the so-called tubular latch bolts for installation and mounting in a mortised or bored opening formed in a closure such as a door. Such latch bolts usually form a unit which comprises a case within which is housed a spring loaded latch bolt for projection to latching position by the biasing action of its spring loading and for retraction to unlatched position against its spring loading. Mechanism is included within the case for actuation to retract the latch bolt while the association of such mechanism and the latch bolt is usually such that the bolt may be depressed to retracted position independently of the retracting mechanism.

It is an object of my invention to provide an improved design and construction of tubular latch bolt unit capable of general use with various types of door latch and lock mechanisms and the so-called door lock sets formed therewith.

Another object is to provide a tubular latch bolt unit adapted for general use as a plain unit of the spindle actuated type, as well as being adapted for efficient use with various special types of door latch mechanisms, such, for example, as the inside door set disclosed in my aforesaid patent.

A further object is to provide a design and construction of tubular latch bolt unit which can be readily manufactured in quantity production at low cost, yet which will insure positive, precision operation of the unit with a minimum of maintenance and structural or operational failures under the various conditions to which subjected in operation and use.

Another object is to provide a tubular case for such a latch bolt unit of a construction which has a minimum of parts of a character to be readily stamped or formed and readily accurately assembled for low-cost quantity production.

2

A further object is to provide such a case designed for cooperative mounting therein in operative assembly, the components of the latch bolt retracting mechanism for functioning of such mechanism with minimum friction yet with precision under all normal operating conditions.

And a further object is to provide an improved and simplified construction and assembly of tubular case mounted-latch bolt retracting mechanism and of the latch bolt operatively assembled therewith.

With the foregoing and various other objects, features and results in view which will be readily apparent from the following detailed description and explanation, my invention consists in certain novel features in design and construction, and in combinations and sub-combinations of parts and elements, all as will be more fully referred to and specified hereinafter.

20 Referring to the accompanying drawings in which similar reference characters refer to corresponding parts throughout the several figures thereof:

Fig. 1 is a view in horizontal section through a 25 latch bolt unit of the invention in mounted, installed position in a door in operative association with a door knob operated latch bolt retracting spindle, a portion only of the door being shown.

Fig. 2 is a view in vertical longitudinal section 30 taken as on the line 2—2 of Fig. 1.

Fig. 3 is an exploded view illustrating in perspective the parts and components making-up the latch bolt unit of the form of the example unit of Figs. 1 and 2, with the parts of the tubular case, 35 the latch bolt unit, and the bolt retracting mechanism being shown separated but in the relative positions thereof to be assumed in assembly.

Fig. 4 is a view in top plan of a portion of the 40 unit, showing particularly the mounting of the bearing plate and roll-back in the case.

A presently preferred form and embodiment of a tubular case latch bolt unit embodying the various features of my invention has been selected and is disclosed herein by way of example 45 in operative installation and associated with a suitable knob operated actuating spindle of any suitable or desired door lock set but without any intention to limit the use of the latch bolt unit to such door lock set or to any other particular set. Referring to Figs. 1 and 2 of the drawings, a portion of a door D is disclosed in which a usual mortised or bored passage or space 2 is formed which extends into the body of the door D through the outer free edge 3 thereof. A 50 tubular latch bolt unit L of the invention is mounted in horizontally disposed position within

the bore 2 in operative association with a door lock or latch set which includes a spindle S mounted in position extended transversely through the door D and the latch bolt unit L. The door D is provided with a circular bored opening 4 which extends transversely through the door across and intersects opening 2 with the axes of these bores 2 and 4 being perpendicular to each other. It is the bore 4 which is provided for and through which the spindle S extends in operative association with the latch bolt unit L. The forward, outer end of unit L is provided with a vertically disposed face plate 107 attached to a back plate 105 secured on the forward end of the case of the unit L. Unit L is mounted in position in opening 2 in the usual manner by attaching the plates 105 and 107 to the door edge by screws 107a, as shown in Fig. 2.

The spindle S is formed in this instance of square cross section (see Fig. 2) and is primarily supported in the example hereof in its horizontally disposed position at the central or intermediate portion thereof which extends through and is received in the latch bolt unit L in operative connection with the latch bolt retracting mechanism therein. The spindle S mounts at its opposite ends and the opposite sides of door D. The inner and outer door knobs I and O, respectively, which are connected therewith in the usual or any desired manner to permit of the spindle S being rotated thereby in either direction by manual turning of either of the knobs. Any suitable outside rose 14 may be provided at the outer side of the door through which spindle S rotatably extends, and similarly a suitable inside rose 15 may be provided at the inner side of the door through which the spindle extends for rotation therein.

The latch bolt unit L of the example embodiment of my invention comprises a case 100 which may be stamped, pressed or otherwise formed from a suitable sheet material to include a side wall 101, opposite edge, parallel walls 102 and 103 connected at one end by an end wall 104. In this instance the wall 102 is shown as the upper wall while wall 103 is the lower one and the wall 104 is the inner end wall of the case with the unit L in installed position in the door D. At the forward end thereof the case 100 is open and the walls 102 and 103 have at their outer end edges the upwardly and downwardly turned tongues 102a and 103a, respectively, by which the case 100 has secured and attached to the forward or outer end thereof the vertically disposed back plate 105. This plate 105 is provided with a central opening 106 therethrough which with the plate in assembled position on the forward end of case 100 is aligned with the open forward end of the case. The complementary face plate 107 is suitably secured on and covering the outer side of the inner or back plate 105. The face plate 107 is provided with a rectangular opening 108 therethrough which is aligned with the opening 106 in the back plate 105. The aligned openings 106 and 108 in the plates 105 and 107 are adapted to slidably receive therein the usual door latch bolt 99 for retraction and projection therethrough in the operation of the latch bolt unit L.

Case 100 is completed by the attachment thereto of a cap 109 which forms the side wall of the case opposite and parallel with the side wall 101. The cap 109 at its forward end is provided with a forwardly extended tongue 109a by which it is secured to the back plate 105 and

face plate 107 in the assembled position of the case. The rear end of the cap 109 is formed with a recess 109b adapted to receive therein a tongue 104a formed on and projecting from the free edge of the inner end wall 104. The tongue 104a fitted into the recess 109b attaches and positions the rear end of the cap 109 on the case 100 in assembled position thereof. The top wall 102 and the bottom wall 103 are each formed of reduced width intermediate their forward and rear ends to provide the elongated, longitudinal seating edges 102b and 103b, respectively. The walls 102 and 103 at their forward ends at the open side of the case which receives the cap 109 thereover, are formed to provide the projecting tongues 102c and 103c, respectively. Seats 102d and 103d are thus formed by the edges of the walls 102 and 103, respectively, which connect the tongues 102c and 103c with the elongated seat forming edges 102b and 103b. The walls 102 and 103 are provided with cut-outs 110 therein which are aligned transversely of the case 100 in positions located intermediate the seating edges 102b and 103b and the inner end wall 104. Transversely parallel tabs 102e are formed from the walls 102 and 103 between the cut-outs 110 and the inner ends of seating edges 102b and 103b, while at the rear sides of the cut-outs 110, walls 102 and 103 are formed to provide the outwardly projecting tabs or tongues 102f, respectively.

The cut-outs or recesses 110 in the walls 102 and 103 provide the similar transversely aligned seats 110a, which seats are extended inwardly and forwardly by undercuts or re-entrant recesses to form in the walls the forwardly extended slots 110b. The wall 101 and the cap 109 of case 100 are formed with the circular openings 111 transversely therethrough respectively, 40 which with the unit in assembled relation are axially aligned for receiving therethrough the latch bolt actuating spindle S.

The case side wall forming cap 109 is formed with the laterally offset, longitudinal edge flanges 109c and the laterally offset transverse inner end flange 109d, in which latter flange the recess 109b is provided. The flanges 109c terminate spaced from the forward end of the cap 109 and the cap is formed intermediate its forward end and the forward ends of flanges 109c 45 with the opposite side, laterally extending tongues 109e and the opposite forward recesses 109f. The offset longitudinal flanges 109c of the cap 109 are formed with the pairs of opposite transversely aligned recesses 109g in locations for receiving therein the pairs of case tongues 102e and 102f, respectively.

In assembled position of the cap 109 on the case 100, tongues 102c and 103c seat in the cap recesses 109f; cap tongues 109e seat on the case seats 102d and 103d; the offset flanges 109c of the cap 109 seat on the elongated longitudinal edge seats 102b and 103b of the case walls 102 and 103, and extend rearwardly over and across the cut-out portions which form the inset seats 110a; the case tongues 102e and 102f are received in the cap recesses 109a, respectively, and case tongue 104a is received and seats in the recess 109b of the offset end flange 109d of the cap 109. The tab or tongue 109a projecting from the forward end of the cap 109 extends through the opening 106 of the back plate 105, being engaged over the adjacent edge portion of that opening, while the tongues 102a and 103a of the case 100 also extend into back plate opening 105

and are engaged over adjacent edge portions of that opening.

The case closing cap 109 thus has in effect a "snap" attachment on and to the case 100 in assembled position thereof, so that it may be readily assembled on the case with the case assembled in attached position to the back plate 105 at the forward end thereof. The tab or tongue 104a may after assembly be bent slightly inwardly over and engaged with the cap to insure against cap displacement. It may be as readily bent outwardly sufficiently to enable ready detachment and removal of the cap 109 from the case 100 in the event that it should become desirable to open the case for repair or replacement of any of the parts of the latch bolt mechanism contained within the case. The complete case itself comprises but two (2) readily manufactured major components, namely, the case 100 and the cap 109, while the latch bolt receiving and mounting structure attached to the forward end of the case 100 comprises but two (2) parts, namely, the back plate 105 and the face plate 107 which are easily manufactured and readily assembled on the forward end of the case.

The mechanism for retracting and projecting the latch bolt 99 is mounted and enclosed within the case 100 and cap 109, and in accordance with my invention such mechanism includes a hub or roll-back mounting, bearing member 112. This bearing member 112 is provided with a circular bore therethrough and is mounted on the spaced seats 110a provided by the cut-outs 110 in walls 102 and 103, with such bearing member in position extending across the case 100 between the wall 101 and the cap 109 with the bore 113 thereof axially aligned with the bores 110 in case wall 101 and in the cap 109. The bearing member 112 is formed with the opposite extended portions forming the flanges 112a which engage and seat upon the seats 110 and at their forward ends are received and engaged in the slots formed by the undercuts 110b respectively, in the walls 102 and 103. The bearing member 112 is formed or provided with the inwardly turned flange 114 across the forward end thereof. This flange 114 is formed curved or arcuate about the axis of the bore 113 as a center. The effective length of this flange 114 is equal to the spacing between the inner surfaces of the walls 102 and 103, so that the flange will fit into position therebetween. A hub or roll-back member 115 having a square opening 116 therethrough which is dimensioned to slidably fit and receive therethrough the spindle S, is provided for rotatable mounting on and against the inner side of the bearing member 112. Hub member 115 is formed to provide the curved forward edge 117 complementary with the inner curved side of the arcuate flange 114 for slidable bearing engagement with such flange. The curved forward edge 117 of roll-back member 115 has its opposite ends extended outwardly beyond the body of the roll-back member to form the upper and lower lugs 118.

A yoke member 120 of generally elongated, rectangular form is slidably mounted and confined within the case 100 for actuation by rotation of the roll-back 115 to retract and project the latch bolt 99. This yoke 120 includes a vertically disposed wall 121 having an elongated opening 122 transversely therethrough with this wall in assembled position of the yoke in the unit disposed and slidable between the inner side of roll-back

member 115 and the outer side wall or cap 109, as will be clear by reference to Fig. 1. At its forward, upper side the yoke 120 has an inwardly bent guide and positioning finger 123 which has 5 slidable engagement at its free end with the inner side of case wall 101. At its forward, lower side the yoke 120 is formed with an inturned flange 124 which also has at its inner free end, slidable bearing engagement with the inner side 10 of the wall 101 of the case 100. The flange 124 is formed with a rectangular opening 125 therethrough. The yoke 120 bridges the roll-back member 115 and the spindle S which extends therethrough in assembled position, and at its 15 rear end between the bearing member 112 and the inner end wall 104 of the case 100, the yoke is bent inwardly for its full width to form the flange 126 thereacross which has slidable bearing engagement with the inner surface of the wall 101, and which together with the finger 123 and the flange 124 at the forward end of the yoke, provides the positioning and aligning support for the reciproctaion of the yoke within the case 100. The yoke 120 has lateral guiding support in the 20 direction of the cap 109 by slidable engagement with the inner side, flat surfaces provided by the 25 portions of the cap contiguous thereto.

The yoke member 120 has formed and bent-up therefrom at the upper and lower side edges of 30 the wall 121, the upwardly and downwardly projected ears 130, respectively. The ears 130 are located on the wall 121 intermediate the length of the elongated opening 122 and in positions at the rear of and engaged by the upper and lower 35 lugs 118, respectively, of the roll-back member 115. Hence, in assembled position the rotation of the roll-back member 115 in either direction by rotation of the spindle S will cause the rearwardly swinging or rocking lug 118 to engage its 40 yoke mounted ear and to thereby force or slide the yoke rearwardly in the case 100 in a direction to retract the latch bolt 99.

The latch bolt 99 of the latch bolt unit L may 45 be considered to be of generally conventional design to provide the usual inclined face or surface for slidable engagement against the strike plate 81 (see Fig. 1) of a door frame. In this instance, the latch bolt 99 is slidably positioned in and guided by the square opening 108 through 50 the face plate 107, and extended inwardly through the opening 106 of the back plate 105 which is attached to the forward end of the case 100. The latch bolt 99 has suitably connected to the rear end thereof a tail piece 131 which extends inwardly a distance into the case 100 and which is 55 provided at its inner end with an upwardly projected nose forming a hook 132. The hooked inner end of the tail piece 131 extends into the rectangular opening 125 of flange 124 of the yoke 60 120 in position with the upwardly extended nose of the hook 132 engageable against the inner side of the flange 124 at the upper side of the opening 125. Upon rearward movement of the yoke 120 within the case 100 the hooked inner end 132 of 65 the tail piece 131 being engaged with the yoke will draw the tail piece rearwardly and retract the latch bolt 99. However, the latch bolt 99 with the tail piece 131 is movable rearwardly relative to and independently of the yoke 120 by rearwardly acting forces applied to the latch bolt 70 at the outer end thereof. Under such conditions the tail piece 131 slides freely rearwardly through the yoke 124 completely independently of the yoke.

75 A coiled expansion spring 133 is mounted on

and over the tall piece 131 under compression between the rear of the latch bolt 99 and the flange 124 of the yoke member 120. Thus, the latch bolt when depressed or moved inwardly relative to the yoke 120 places the spring 133 under increased compression, so that upon release of the inwardly acting forces on the latch bolt the latter is instantly projected outwardly to normal strike-engaging, door latching position.

The yoke member 120 is spring loaded and normally continuously biased to its forwardly projected position. With the unit L of my present invention the spring loading of the yoke 120 is provided by a coiled expansion spring 134 which is inserted under compression within the case 100 between the inner end wall 104 of the case and the inner end flange 126 of the yoke 120. When the roll-back 115 is rotated in either direction by spindle S which extends transversely therethrough in driving connection therewith in assembled position, the yoke 120 is forced rearwardly against the spring 134 and the latch bolt is retracted. Upon release of the turning forces on the spindle S the spring 134 acts to instantly move the yoke 120 forwardly to return it to normal, latch bolt projected position. When the latch bolt 99 is retracted by rearward movement of the yoke 120 against the spring 134, the spring 133 is not further compressed. However, when the latch bolt 99 is depressed and retracted independently of the yoke 120, the spring 133 is compressed and in order to permit of such compression spring 134 must not yield to the forces applied to the yoke by the spring 133. Hence, spring 134 is formed heavier to exert a force greater than that of the spring 133, so as to be unyielding under such conditions.

By the foregoing design, construction and assembly I have produced a door latch bolt unit of extreme mechanical simplicity with a minimum of parts each of which may be readily manufactured by low-cost quantity production and which parts lend themselves to ready, time assembly with assurance of proper operative relation of the parts when assembled. With the two-part pressed or stamped case a light-weight structure is produced with close tolerances and without the need for expensive finishing operations. The case structure with its "snap-on" cover plate is readily assembled and disassembled, while providing an exteriorly clean case. The design and assembly of the case with the bearing plate mounting provided therefor, not only makes for ease of assembly but insures in a minimum friction and wear arrangement when assembled in operative relation in the case with the roll-back and the latch bolt retracting yoke.

It will also be evident to those skilled in the art that various changes, variations, modifications, substitutions, eliminations and additions might be resorted to without departing from the broad spirit and scope of my invention, and hence I do not intend or desire to limit my invention in all respects to the exact and specific disclosures hereof, except as may be required by intended specific limitations thereto appearing in any of the appended claims.

What I claim is:

1. In a tubular latch bolt unit, in combination, a tubular case including spaced opposite edge walls and a side wall connecting said edge walls at one side thereof, said case being open at the side thereof opposite said side wall, said opposite edge walls being formed with transversely aligned cut-outs therein opening through the free edges

70 75

thereof, respectively, to provide inset seats, a bearing plate member mounted on said seats in position extending across and between said edge walls within the case intermediate said side wall

5 and the opposite open side of said case, said bearing plate member being formed with a bore transversely therethrough and being provided at one edge thereof transversely of said case with an inwardly extended arcuate flange, a roll-back 10 mounted in position against the inner side of said bearing plate member, said roll-back having an arcuate edge in slidable bearing engagement with said arcuate flange of said bearing plate member, said roll-back being adapted for rotation about 15 the axis of said bearing plate member bore, and a closure cap attached to said case over and closing the open side thereof in position spaced from said roll-back when the latter is in operative mounted position on said bearing plate member.

2. In a tubular latch bolt unit, in combination, a case formed to provide a side wall, spaced opposite edge walls and an end wall closing one end of the case, the opposite end of the case and the side thereof opposite said side wall each being open, said opposite edge walls each being of reduced width along intermediate portions thereof to form elongated inset seating edges therealong, each of said edge walls being provided with a cut-out therein to provide an inset seat intermediate said end wall and the adjacent end of said reduced width portion of the edge wall, tongues on each of said edge walls projecting outwardly from the free edge thereof at locations thereon intermediate said end wall and said inset 35 seat at one end of the case and at the opposite end thereof intermediate said open end and the adjacent end of the reduced width portion of said edge wall, a bearing plate member mounted on said inset seats in position extending transversely through said case between said edge walls and intermediate said side wall and the opposite side of said case, a cap member mounted in position seated on said elongated seating edges of said edge walls over and closing the open side of said case spaced from said bearing plate member, and said cap member being formed with 40 seats formed in the edges thereof adapted to be engaged by said tongues, respectively, to maintain said cap in position on and closing said case.

3. In a latch bolt unit, in combination; a tubular case including spaced opposite edge walls each having a portion thereof cut-out inwardly through an edge of the wall to provide therein an inset edge disposed longitudinally of the wall intermediate the opposite side edges thereof to form an inset seat; said seat forming edges being aligned transversely of said case and ends of said edges being extended by undercuts in said walls, respectively, to form retaining slots into which said seats extend; and a substantially flat bearing plate member mounted on said seats and received in said retaining slots in position extending across said case between said opposite edge walls.

4. In a tubular latch bolt unit, in combination; a case providing a side wall, an end wall, and spaced opposite edge walls to form a case open at one side and at one end thereof; said opposite edge walls being provided with recesses forming inset seats therein, respectively, aligned transversely of said case intermediate the open side and said side wall of the case; a bearing plate member mounted on said transversely aligned seats in position extending transversely through the interior of said case between said opposite edge walls and spaced from said side wall and

said open side of said case; said bearing plate member having a centrally located bore therethrough and being formed along one edge thereof with a flange extending laterally from the side of said plate member facing the open side of said case; said flange at the inner side thereof facing said plate member bore being formed to provide an arcuate bearing surface having the axis of said bore as a center; a rollback rotatably mounted in bearing engagement against the side of said bearing plate member facing the open side of said case for rotation about the axis of said bore; the edge of said rollback adjacent said bearing plate member flange being provided with an arcuate bearing surface complementary to and in bearing engagement with the arcuate bearing surface of said flange; and a plate-like closure cap attached to said case over and closing the open side thereof; said rollback and said closure cap being formed in assembled positions thereof to form a space therebetween within said case.

5. In a tubular latch bolt unit, in combination; a tubular case including spaced opposite side walls and spaced opposite edge walls, said case being closed at one end by an end wall and being open at the opposite end; a bearing plate member mounted at opposite edge portions thereof on said opposite edge walls, respectively, in position extending therebetween through said case intermediate and spaced from said opposite side walls; a rollback rotatably mounted in position in bearing engagement against one side of said bearing plate member for rotation thereon about an axis transverse of the plane of said bearing plate member; a yoke member reciprocably mounted in said case between said roll-back and the adjacent side wall of said case; said yoke member at its opposite ends having laterally inwardly projected flanges in sliding bearing engagement at their outer ends at opposite sides, respectively, of said bearing plate member with the adjacent side wall of said case; said yoke member at the end thereof adjacent the open end of said case having an end wall formed with an opening therethrough adapted to receive therein a latch bolt; and an expansion spring loosely mounted in the space between said end wall of the case and said flange on the adjacent end of said yoke and being confined under compression between said end wall and such flange.

6. In a latch bolt unit, in combination, a tubular case formed with one side wall, one end wall, and opposite edge walls to form a case open at one side and at one end thereof, and a plate-like closure cap fitted over said open side to close said case; said opposite edge walls being provided with cut-out portions therein opening through the side edges thereof to form transversely aligned edges disposed longitudinally of said case providing seats spaced inwardly thereof from and intermediate said side wall and said closure cap; the adjacent ends of said edges of said cut-out portions being extended inwardly by undercuts in said edge walls, respectively, to provide retaining slots therein; a substantially flat bearing plate member having planar opposite side surfaces, said bearing plate member being engaged at its opposite ends on said edge wall seats in position extending across said case between said opposite edge walls and intermediate and spaced from said side wall and said closure cap; said bearing plate member being provided with portions thereof extending into said retaining slots to secure said bearing plate

member in mounted position in said case; said bearing plate member having a bore transversely therethrough; and a rollback member mounted in position at one side of said bearing plate member in bearing engagement with the planar surface thereof for rotation about the axis of said bore in said bearing plate member.

7. In a latch bolt unit, in combination; a tubular case including spaced opposite walls; said walls being formed to provide seats therein aligned transversely of said case; a bearing plate member mounted on said seats in position extending transversely of said case through the interior thereof between and intermediate the opposite edges of said spaced walls; said bearing plate member having a bore therethrough and being formed across one end thereof with a guide flange provided at the inner side thereof facing said plate member bore with an arcuate bearing surface generated about the axis of said bore as a center; a rollback member at one side of said bearing plate member mounted for rotation about the axis of said bore in bearing engagement against the adjacent side of said bearing plate member; and said rollback being formed with an arcuate bearing surface thereon in bearing engagement with the arcuate bearing surface of said guide flange.

8. In a latch bolt mechanism, in combination; a tubular case including spaced opposite walls; said walls being formed to provide seats therein aligned transversely of said case; a bearing plate member mounted on said seats in position extending through the interior of said case between and transversely of said spaced walls and having a centrally located bore transversely therethrough; said bearing plate member having one edge portion thereof formed to provide an arcuate flange extending laterally of said plate member from one side thereof spaced from and being generated about the axis of said bore as a center; and a rollback member mounted for rotation at and in bearing engagement against the side of said bearing plate member from which said arcuate flange extends; and said rollback being mounted for rotation about the axis of said bore and the edge thereof adjacent said arcuate flange being formed for bearing engagement thereon.

9. In a tubular latch bolt unit, in combination; a tubular case including a side wall and spaced opposite edge walls with the side of said case opposite said side walls being open; said opposite edge walls having cut-outs therein providing inset edges forming seats in said edge walls, respectively, aligned transversely of said case; a closure cap member attached to said case over and closing the open side thereof; a substantially flat bearing plate member mounted on said inset seats in said edge walls in position extending across and bridging said case therewithin between said edge walls intermediate but spaced from both said side wall and said closure cap member; said bearing plate member having a bore transversely therethrough and being formed to provide a substantially planar bearing surface at the side thereof facing and spaced from said closure cap member; and a rollback member mounted at the side of said bearing plate member facing said closure plate member for rotation about the axis of said bore through said bearing plate member in bearing engagement with said planar bearing surface thereof.

10. In a latch bolt mechanism, in combination; a tubular case including spaced opposite

11

walls; a substantially flat bearing plate member mounted in position extending through the interior of said case between said spaced walls intermediate the opposite edges thereof; said bearing plate member having a bore transversely therethrough and having one edge thereof formed to provide an arcuate flange extending laterally of said plate member from one side thereof spaced from and being generated about the axis of said bore as a center; a substantially flat, plate-like rollback member mounted in position in said case for rotation at and in bearing engagement against the side of said bearing plate member from which said arcuate flange extends; and said rollback member at the edge portion thereof adjacent said arcuate flange being formed to provide an arcuate surface for bearing engagement on said arcuate flange.

11. In a tubular latch bolt unit, in combination; a tubular case including spaced opposite side walls and spaced opposite edge walls; a substantially flat bearing plate member mounted at opposite edge portions thereof on said opposite edge walls, respectively, in position extending therebetween through said case intermediate and spaced from said opposite side walls; said bearing plate member having a bore transversely therethrough; a substantially flat rollback member rotatably mounted in position for bearing

12

engagement against one side of said bearing plate member for rotation thereon about the axis of said bore in said bearing plate member and being spaced from the adjacent of said opposite side walls of said case; said rollback member having a bore therethrough for axial alignment with said bearing plate member bore; a yoke member reciprocably mounted in said case across and between said rollback and the adjacent side wall of said case adapted to retain said rollback against displacement laterally from position at said bearing plate member; and said yoke member being provided with an elongated slot therethrough opposite and aligned with said aligned rollback member and bearing plate member bores and at its opposite ends having lateral inwardly projecting flanges in sliding bearing engagement at their outer ends with the adjacent wall of said case at opposite sides, respectively, of said bearing plate member.

GOTTHARD HAGSTROM.
